John B. Virga INVENTOR.

BY
Geo. P. Kimmel
ATTORNEY.

ATTORNEY.

UNITED STATES PATENT OFFICE

JOHN B. VIRGA, OF WASHINGTON, DISTRICT OF COLUMBIA

SASH WINDOW

Application filed November 29, 1930. Serial No. 499,066.

This invention relates to a sash window and has for its primary object to provide, in a manner as hereinafter set forth, a window of such class in which the sashes may be readily swung to angular positions with respect to the frame to facilitate the cleaning of the sashes and to obtain greater ventilation than is possible in sash windows of ordinary construction.

10 A further object of the invention is to provide a sash window of the character aforesaid in which the sashes are provided with pins slidable relative to the frame for pivotally supporting the sashes when the latter are angularly extended with respect to the frame and in which the pins serve as anti-rattle devices when the sashes are normally disposed with respect to the frame.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

20 In the accompanying drawings in which like numerals are employed to designate like parts throughout the several views:

Figure 1 is a sectional, front elevation of a sash window in accordance with this invention, the view being taken substantially at the point indicated by the line 1-1 of Figure 3.

Figure 2 is a vertical section through the window showing the sashes in angular relation to the frame.

Figure 3 is a vertical section through the window showing the normal position of the sashes with respect to the frame.

Figure 4 is a horizontal section taken at the point indicated by the line 4-4 of Figure 3.

Figure 5 is an enlarged fragmentary sectional elevation of one of the sashes and one of the inner side members of the frame.

50 Figure 6 is an enlarged perspective view

of the removable portion of one of the dividing strips.

Figure 7 is an enlarged fragmentary section through the removable portion of one of the dividing strips and through one of the inner side members of the frame.

Referring to the drawings in detail, the numeral 1 indicates generally a window frame formed at its sides with inner side members 2 and outer side members 3 which are connected together by means of rear members 4 and front members 5 to provide the usual weight chambers 6. Forwardly of the front members 5, the frame is provided with the usual facing strips 7, the members 2, 3, 4, 5 and 7 being seated in the usual manner on a sill 8.

Slidably mounted between the inner frame members 2 is an upper sash 9 and a lower sash 10. The rear members 4 project inwardly beyond the inner side members 2 to provide abutments for the rear face of the upper sash 9. Centrally thereof, the side members 2 are formed in their opposing faces with vertically extending grooves 11 within the upper portions of which are secured stationary dividing strip portions 12, and within the lower portions of which are positioned removable dividing strip portions 13 in vertical alignment with the portions 12. The strips 12 and 13 provide abutments for the forward face of the upper sash 9 and for the rearward face of the lower sash 10. The lower sash 10 is abutted at its forward face by stationary retaining strips 14 secured to the front members 5, and by movable retaining strips 15 which are hinged to the front members 5 and which normally extend in vertical alignment with the strips 14.

Embedded in the inner side members 2 and front members 5 are a pair of plates 16 which are formed with slots 17 forwardly and upwardly curved at their lower ends. In alignment with the slots 17, the side members 2 are formed with grooves 18 which are substantially of greater area in cross section than the width of the slots and which gradually decrease in depth in an upward direction from a point in spaced relation to the upper ends of the plates 16. Adjacent

cent each side thereof, the lower sash 10 is formed in its upper face with a recess 19 within which extends a pair of spaced lugs 20 depending from a plate 21 flush with the upper face of the sash. Slidably extending through the lugs 20 of the plates 21 are plungers 22 which are adapted to extend through the slots 17 of the plate 16, and which are provided on their outer ends with heads 23 which are slidably disposed in the grooves 18 when the plungers are extended through the slots 17. Each plunger 22 is resiliently forced outwardly by means of a spring 24 which encircles the plunger, and the respective ends of which abut one of the lugs 20 and a pin 25 extending through the plunger and located between the lugs. The outer ends of the plates 21, as well as the side faces of the sash 10, are recessed as indicated at 26 for the reception of the sash portion 27 for the sash 10. The plates 16 are disposed at a proper height to position the plungers 22 within the slots 17 when the sash 10 is in its lowered or closed position as shown in Figure 3.

Embedded in the side members 2 and rear members 4 are a pair of arcuate plates 28 which are formed with arcuate slots 29 which curve upwardly at their lower ends. In alignment with the slots 29 are grooves 30 in the side members 2, the grooves 30 being of substantially greater cross sectional area than the width of the slots 29. Projecting from the side faces of the upper sash 9, adjacent the upper face of the latter, are plungers 31 similar in every respect to the plungers 22 heretofore described. The plungers 31 are adapted to extend through the slots 29 and to have the heads thereof slidably disposed within the grooves 30. The plates 28 are arranged below the plates 16 and are of a proper height to receive the plungers 31 through the slots 29 when the upper sash is in its lowered or opened position.

The removable dividing strip portions 13 extend across the plates 28 and are provided in their outer side faces with notches 32 for the reception therein of the plates. The portions 13 are maintained in position by means of headed pins 33 which depend therefrom into recesses 34 in the sill 8, and by means of latch plates 35 which are provided centrally thereof with resilient, split tongues 36 which frictionally engage central portions 37 of latch members 38 secured to the side members 2 and which extend across and conform in contour with the walls of the grooves 11. The central portions 37 of the members 38 correspond in contour to the tongues 36 on the latch plates 35.

Extending through suitable openings in the facing strips 7 are a pair of chains 39 which are provided at their outer ends with hooks 40, and which have suitable weights 41

secured to their inner ends and disposed within the chamber 6. The sashes 9 and 10 are provided with suitably spaced, counter-sunk hooks such as 42 for engagement with the hooks 40 of the chains 39. The sashes 9 and 10 are provided with suitable handle members 43 and are also provided with the usual latch 44.

If it is desired to clean the outer face of the window carried by the lower sash 10, the hinged strips 15 are swung forwardly as shown in Figure 2, and the sash is raised a sufficient distance to clear the abutment strip 45 seated on the sill 8. The lower end of the sash then may be swung in a forward and upward arc, causing the plungers 22 to ride along the slots 17 and enabling the sash to be inverted with the outer face thereof disposed inwardly.

If it is desired to clean the outer face of the upper sash 9, the removable dividing strip portions 13 are removed and the sash 9 is slid downwardly with respect to the frame, after which the lower end thereof may be swung in a forward and upward arc in the same manner as above described in connection with the lower sash 10. The upper sash 9 may be swung at an angle with respect to the frame either with the lower sash 10 in an angular position as shown in Figure 2 or in its normal open position between the retaining strips 14 and the stationary dividing strip portions 12. If it is desired to anchor either or both of the sashes in angular relation to the frame, this may be accomplished simply by engaging the hooks 40 of the chains 39 with the hooks 42 of the sashes.

It is thought that the many advantages of a sash window in accordance with this invention will be readily apparent, and although the preferred embodiment of the invention is as illustrated and described, it is to be understood that changes in the size, shape and arrangement of parts may be resorted to, so long as such changes fall within the scope of the invention as defined in the appended claims.

What I claim is:

1. A sash window comprising, a frame, an upper and a lower sash slidable in the frame, plates having arcuate slots connected with the frame, and plungers projecting from the sashes into said slots for pivotally connecting the sashes with the frame, said frame having grooves in alignment with said slots, said plungers having heads disposed within said grooves, said plungers having resilient means for forcing the heads towards the frame.

2. A sash window comprising, a frame, upper and lower sashes disposed in separate vertical planes and slidable in the frame, and spring pressed plungers projecting from opposite sides of each sash into engagement with the frame, said frame having arcuate

grooves for receiving said plungers to pivotally connect the sashes with the frame.

3. A sash window comprising, a frame, upper and lower sashes disposed in separate vertical planes and slidable in the frame, and projections on opposite sides of each sash, said frame having arcuate grooves for receiving said projections to pivotally connect the sashes with the frame, said arcuate grooves being located substantially midway 10 of the height of the frame.

4. A sash window comprising, a frame, upper and lower sashes disposed in separate vertical planes and slidable in the frame, 15 spring pressed plungers projecting from opposite sides of each sash, and plates secured to the frame and having arcuate slots for receiving said plungers to pivotally connect the sashes with the frame.

20 In testimony whereof I affix my signature hereto.

JOHN B. VIRGA.
